T. S. LORD

WATER CLOSET ACCESSORY

Filed Aug. 8, 1927

Inventor

J. S. Lord
Seymour & Bright

Attorney,

UNITED STATES PATENT OFFICE.

THOMAS SEAGRAVE LORD, OF DUNEDIN, FLORIDA.

WATER-CLOSET ACCESSORY.

Application filed August 8, 1927. Serial No. 211,491.

This invention relates to improvements in water closet accessories and more particularly to adjustable means for causing the body to assume a proper position to facilitate defæcations,—one object is to provide a simple structure which shall be adjustable for persons of different proportions, including children as well as grown persons, and which shall be operable to cause the lower limbs to assume such position that the act of defæcation shall be assisted.

With this and other objects in view, the invention consists in certain novel features of construction and combinations of parts 15 as hereinafter set forth and pointed out in the claims.

In the accompanying drawings;

Figure 1 is a view illustrating an embodiment of my invention, and

20 Figure 2 is a plan view.

My improvements are to be associated with a water closet bowl of any preferred style and over which a seat is provided as is well understood in the art.

25 The base frame 1 of my improved attachment (which may be a casting) is approximately U-shaped so that it may be caused to partially embrace the base of the bowl, with the members 2, 2 of said frame at 30 the sides of the bowl and the connecting member 3 in front of the bowl, and said base frame will preferably be provided with rubber feet 4 which by their frictional engagement with the floor will prevent the device from sliding.

35 Lugs 5, 5, project upwardly from each of the side members 2 of the base frame 1 and with these lugs, pairs of parallel links 6, 6^a are pivotally connected. These links extend 40 forwardly and upwardly from their connection with the base frame, so that they will be inclined. The upper forward end portions of the links 6 of the respective pairs of parallel links are connected with lugs 7 depending 45 from lateral extensions 8 of castings 9 and the links 6^a are pivoted to lugs 7^a near the other ends of said castings. These castings constitute supports for a platform or foot board 10, the rear edge portion of which 50 is recessed as at 10^a to avoid conflict with the front part of the bowl while being adjusted and to permit the user to draw his feet well back and assume a natural squatting position.

55 Standards 11 project upwardly from re-

spective members 2 of the base frame 1 and curve rearwardly. Each standard is provided on one edge with ratchet teeth 12. Brackets 13 are secured to the under side of the platform or foot board 10 and each of 60 these brackets carries a pivoted dog 14 which engages the toothed standards in a manner to retain the platform or foot board 10 in any desired position of vertical adjustment. A spring 15 bears against each dog so that 65 the dogs may ride over the ratchet teeth of the standard when the board 10 is raised from a lower to an upper position of vertical adjustment. The dogs are provided with handles 16 which may be manipulated to 70 disengage said dogs from engagement with the ratchet teeth of the standards when it is desired to move the board 10 to a lower position of vertical adjustment.

75 Downward movement of the platform or foot board 10 may be limited by lugs 17 on the lower portions of the standards to be engaged by the links 6. Lugs 18 near the upper ends of the standards serve, by cooperation with the links 6, to limit the upward 80 movement of the platform or foot board 10.

It will be readily seen that by means of my improvements, the foot board may be easily adjusted vertically and also rearwardly or forwardly relatively to the bowl seat, so that 85 it may be made to accommodate persons of different proportions, including children as well as grown persons.

When the device is in use, the user will be 90 in a squatting position with his feet upon the foot board near the side edges thereof, and stops 19 to receive the heels of the user's shoes will be suitably located upon the foot board near the rearwardly projecting side portions thereof. With my improvements, 95 the lower limbs of the user will be made to take positions that will cause the body to assume such natural position as will facilitate the operation of defæcation, and tendency toward constipation will be prevented.

100 Having fully described my invention what I claim as new and desire to secure by Letters-Patent, is:—

1. In a device of the character described, the combination with a base frame adaptable 105 to the base portion of a water closet bowl, of a foot board, pairs of parallel links pivotally connected with said foot board and said base frame, curved standards projecting upwardly from the base frame and having 110

ratchet teeth, and spring-pressed dogs carried by the under side of the foot board and cooperable with the ratchet teeth of the standards.

- 5 2. In a device of the character described, the combination with a base frame adaptable to the base portion of a water closet bowl, of a foot board, pairs of parallel links pivotally connected with said foot board and said base
- 10 frame, curved standards projecting upwardly from the base frame and having ratchet teeth, spring-pressed dogs carried by the under side of the foot board and cooperable with the ratchet teeth of the standards,
- 15 and handles on said dogs.
- 3. In a device of the character described, the combination with an approximately U-shaped base frame, of a foot board, pairs of parallel links pivotally connected with the
- 20 foot board and with the base frame, curved standards projecting upwardly from the base frame and having ratchet teeth, brackets secured to the under side of the foot board, pivoted spring-pressed dogs mounted
- 25 in said brackets and cooperable with the toothed standards in a manner to retain the

foot board at any desired position of vertical adjustment.

4. In a device of the character described, the combination of a base frame, a foot ³⁰ board, pairs of links pivotally connected with the foot board and with the base frame, standards projecting upwardly from the base frame, stops on said standards and cooperable with a link of each pair to limit vertical movement of the foot board, and means carried by the foot board and cooperable with the standards to retain the foot board at any desired position of vertical adjustment. ³⁵

5. In a device of the character described, the combination with a base frame, a vertically adjustable foot board supported by said base frame, said foot board having a recessed rear portion forming rearwardly ⁴⁰ projecting side portions, and stops on the foot board near the side portions thereof to receive heels of the user's shoes. ⁴⁵

In testimony whereof, I have signed this specification.

THOMAS SEAGRAVE LORD.
